UNITED STATES PATENT OFFICE.

CLARENCE C. LONGARD, OF HALIFAX, CANADA.

WRENCH.

SPECIFICATION forming part of Letters Patent No. 787,778, dated April 18, 1905.

Application filed July 15, 1904. Serial No. 216,671.

To all whom it may concern:

Be it known that I, CLARENCE C. LONGARD, a citizen of Canada, residing at Halifax, in the Province of Nova Scotia and Dominion of Canada, have invented new and useful Improvements in Wrenches, of which the following is a specification.

My invention pertains to wrenches, more particularly wrenches of the sliding and swing-outer jaw type; and it has for its object to provide a wrench embodying such construction that a large amount of thread is contained in the adjusting-nut and the thread is disposed where it cannot be stripped or otherwise injured incident to handling and use of the wrench and one in which sturdy means are provided for taking the thrust.

With the foregoing in mind the invention will be fully understood from the following description and claims when taken in connection with the accompanying drawings, forming part of this specification, in which—

Figure 1 is a side elevation of the wrench constituting the present and preferred embodiment of my invention with a portion of the handle broken away. Fig. 2 is a perspective view of the sliding and swinging jaw of the wrench removed. Fig. 3 is a detail perspective view of the cradle which carries the sliding and swinging jaw. Fig. 4 is a transverse section taken in the plane indicated by the line 4-4 of Fig. 1 looking in the direction indicated by arrow, and Fig. 5 is a similar view taken in the plane indicated by the line 5-5 of Fig. 1 looking in the direction indicated by arrow.

Similar letters designate corresponding parts in all of the views of the drawings, referring to which—

A is the handle of my novel wrench, which has a fixed and preferably-toothed jaw *a* at its forward end, which jaw is concave at its inner side, as indicated by *b*.

B is the sliding and swinging jaw, provided with a shank *c*, which has abutments *d* preferably on its exterior edge and terminates at its inner end in a saddle or bifurcated portion *e*, arranged to straddle the handle A, Fig. 4.

C is the cradle for the sliding and swinging jaw, and D is the nut for adjusting and ad-

justably fixing the sliding and swinging jaw with respect to the cradle.

The cradle C, Fig. 3, is preferably formed of one piece of steel or other suitable metal and comprises an outer portion *f*, apertured, as indicated by *g*, to receive the handle A, and having rounded portions *h* fitting in the cavities *b* of the fixed jaw *a*; a transverse portion *i*, which forms the upper wall of the aperture *g* and is adapted to bear on one edge 55 of the handle A, and parallel rearwardly-extending and exteriorly-threaded portions *i*, disposed at opposite sides of the shank *c* on jaw B. The nut D surrounds the shank *c* of jaw B and surrounds and engages the 60 threaded portions *i* of cradle C, and it is interposed between the abutments *d* of shank *c* and arranged at the outer or forward side of the saddle or bifurcated portion *e* thereof, as shown. By reason of the arrangement of the 65 nut D at the outer or forward side of the saddle *e* the inner or rear abutment *d* on shank *c* is not essential, although I prefer to employ two abutments *d* in order to assure free and easy turning of the nut.

In the practical operation of my novel wrench it will be observed that when the nut D is turned on the threaded portions *i* of the cradle C said nut and the jaw B will be moved longitudinally of the wrench in one direction 70 or the other, according to the direction in which the nut is turned. It will also be observed that in virtue of the cradle C being pivoted at *j* to the handle A, as best shown in Fig. 5, the cradle and the jaw B are free to swing on 75 the handle after the manner common to wrenches of the Stilson type. It will further be observed that the location of the threaded portions *i* of the cradle C is such that liability

of the thread being stripped or otherwise injured incident to handling and using of the wrench is reduced to a minimum and that the transverse portion *i* and the saddle *e* constitute strong and durable means for taking 80 the thrust incident to the manipulation of the wrench and contribute materially to the strength of the wrench as a whole. The saddle *e* also serves the purpose of relieving lateral strains imposed on the jaw B.

As will be readily appreciated from the fore- 85

going, my novel wrench is susceptible of being readily adjusted to pipes and the like of various diameters and is calculated to take a strong and reliable hold, also that the wrench 5 is simple and inexpensive in construction and embodies no frail parts likely to be broken or to get out of order after a short period of use. In this connection it will be noticed that only that part of the bifurcated portion of 10 the cradle subjected to strain is the part occupied and reinforced by the shank *c* of the jaw *B*.

I have entered into a detailed description of the construction and relative arrangement of the parts embraced in the present and preferred embodiment of my invention in order 15 to impart a full, clear, and exact understanding of the said embodiment. I do not desire, however, to be understood as confining myself to such specific construction and relative 20 arrangement of parts, as such changes or modifications may be made in practice as fairly fall within the scope of my invention as claimed.

Having described my invention, what I 25 claim, and desire to secure by Letters Patent, is—

1. In a wrench, the combination of a handle, a jaw carried thereby, a cradle mounted to rock on the handle and having exteriorly-threaded 30 portions, a jaw having a shank disposed between the exteriorly-threaded portions of the cradle and provided with abutments, and a nut interposed between the said abutments of the shank and surrounding and engaging the threaded portions of the cradle.

2. In a wrench, the combination of a handle provided with a jaw, a cradle fulcrumed on the handle and having a transverse portion arranged to bring up against the handle, and also 40 having exteriorly-threaded portions, a jaw having a shank disposed between the exteriorly-threaded portions of the cradle and provided with an abutment and a saddle, the latter being arranged to straddle the handle, and a nut 45 interposed between the saddle and the other abutment of the shank and surrounding and engaging the threaded portions of the cradle.

3. In a wrench, the combination of a handle, a jaw carried by the handle and having concave 50 cavities at its inner side, a cradle having an apertured portion receiving the handle and pivotally connected thereto and provided with rounded portions complementary to the concavities of the jaw, and also having a trans-

verse portion arranged to bring up against the handle, and rearwardly-extending, exteriorly-threaded portions, a jaw having a shank disposed between the threaded portions of the cradle, and having an abutment and a saddle, the latter being arranged to straddle the handle, and a nut interposed between the saddle and the other abutment of the shank and surrounding and engaging the threaded portions of the cradle.

4. In a wrench, the combination of a handle, 65 a jaw carried by the handle, a cradle mounted to rock on the handle and having exteriorly-threaded portions, a jaw having a shank disposed between the exteriorly-threaded portions of the cradle and provided with abutments, and also provided on its rear portion with a saddle arranged to bring up against the handle, and a nut interposed between the abutments of the shank and surrounding and engaging the threaded portions of the cradle. 70

5. In a wrench, the combination of a handle, a jaw carried thereby, a cradle mounted to rock on the handle and having exteriorly-threaded portions, a jaw having a shank disposed between the exteriorly-threaded portions of the cradle, and an interiorly-threaded nut carried by and movable with the shank, and surrounding and engaging the threaded portions of the cradle. 80

6. In a wrench, the combination of a handle, 85 a jaw on the outer end thereof, a rocking cradle carried by the handle and provided with a thread, a jaw having a shank guided by the cradle and provided on its inner portion with a saddle arranged to straddle the handle, and a nut carried by and movable with the shank and engaging the threaded cradle. 90

7. In a wrench, the combination of a handle, a jaw on the outer end thereof, a rocking cradle carried by the handle and provided with a thread, 95 a jaw having a shank guided by the cradle and provided on its inner portion with a saddle arranged to straddle the handle, and means on the cradle for adjusting and adjustably fixing the jaw and its shank with respect thereto. 100

In testimony whereof I have hereunto set my hand in presence of two subscribing witnesses.

CLARENCE C. LONGARD.
